US0D1085419S

(12) **United States Design Patent** (10) **Patent No.:** **US D1,085,419 S**
(45) **Date of Patent:** **** Jul. 22, 2025**

(54) **DENTAL CLEANING MACHINE**

(71) Applicant: **Yuehong Shi**, Guangdong (CN)

(72) Inventor: **Yuehong Shi**, Guangdong (CN)

(**) Term: **15 Years**

(21) Appl. No.: **29/892,832**

(22) Filed: **May 23, 2023**

(30) **Foreign Application Priority Data**

May 17, 2023 (EM) 015021689-0001

(51) **LOC (15) Cl.** **24-02**

(52) **U.S. Cl.**

USPC **D24/176; D24/217**

(57) **CLAIM**

The ornamental design for a dental cleaning machine as
shown and described.

DESCRIPTION

FIG. 1 is a front, left and top perspective view of a dental
cleaning machine, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an exploded view thereof.

The broken lines depict portions of the dental cleaning
machine that form no part of the claimed design.

1 Claim, 9 Drawing Sheets
